UNITED STATES PATENT OFFICE.

FRANK M. STEINER, OF MINNEAPOLIS, MINNESOTA, ASSIGNOR TO STEINER SALES COMPANY, OF SALT LAKE CITY, UTAH, A CORPORATION OF UTAH.

TOWEL CABINET.

Application filed January 31, 1922. Serial No. 533,052.

To all whom it may concern:

Be it known that I, FRANK M. STEINER, a citizen of the United States, resident of Minneapolis, county of Hennepin, State of Minnesota, have invented certain new and useful Improvements in Towel Cabinets, of which the following is a specification.

The object of my invention is to provide a towel cabinet adapted to be equipped with a plurality of clean towel webs so that when one web is exhausted, the use of the second web may be begun without interruption. Oftentimes in the use of a towel cabinet of this type, the person in charge of filling the cabinet with clean towels will find a third or more of one towel unused, too much to be taken out and returned to the laundry and not enough to last until the next trip. If a plurality of webs are used, the laundryman, or janitor, if he finds one web entirely exhausted, may take away the soiled towel and substitute a clean one therefor, thus supplementing the remaining web, and providing a sufficient quantity of clean towel to last until the laundryman makes another trip. If he finds only a small portion of one towel has been used, and another is untouched, then he can be assured that the supply is sufficient without making any change. Provision is also made so that the user may grasp the clean towel web, successively using the one in front and only having access to others when the first one has been exhausted. I am thus able to maintain a continuous supply of clean towel and insure the occupants of a building against a cabinet being inoperative or useless because of the frequent exhaustion of the clean towel supply.

My invention consists generally in various constructions and combinations, all as hereafter described and particularly pointed out in the claims.

In the accompanying drawings forming part of this specification,

Figure 1 is a front elevation of a towel cabinet embodying my invention.

Figure 2 is a vertical sectional view on the line 2-2 of Figure 1,

Figure 3 is a sectional view on the line 3-3 of Figure 2,

Figure 4 is a front elevation of a modified construction,

Figure 5 is a sectional view on the line 5-5 of Figure 4,

Figure 6 is a front elevation of another modification,

Figure 7 is a sectional view on the line 7-7 of Figure 6,

Figure 8 is a detail sectional view of the 60 towel grippers,

Figure 9 is a sectional view on the line 9-9 of Figure 8,

Figure 10 is a sectional view on the line 10-10 of Figure 8.

In the drawing, 2 represents the front of the cabinet and 3 the side walls and 4 the rear panel or wall. An inwardly and downwardly inclined shelf 5 is provided at the top of the wall 2, above which is an opening 70 to allow the user to reach in and grasp the towel and pull it forward to a position for use.

In the lower forward portion of the cabinet is a chamber 6 adapted to receive the 75 soiled towel, a door 7 in the front wall allowing access to this chamber. A wall 8 separates the soiled towel chamber from compartments 9 and 9^a, wherein rolls of clean towel 10 and 10^a are placed, access to 80 said chambers being had through openings in the rear of the cabinet. I prefer to provide a wall 11 separating the chamber 9 from the chamber 9^a and forming a support for the roll 10^a. The roll 10 preferably rests upon 85 the bottom of the cabinet. The loose end of the towel is carried out of the opening at the rear of the compartment 9 and upwardly guided by the wall 11 and guards 12 at the top of the rear wall or panel 4. From these 90 guards the towel passes over a guide-rod 13, removably supported in guides 14 on the side walls of the casing, and from thence the towel is carried through the forward gripper to a point within convenient reach 95 of the user standing in front of the cabinet.

This forward gripper comprises stationary plates 15 and 15^a having their ends secured to the side walls of the casing by suitable means, such as rivets 16, and rigidly supported between said walls by the removable rod 17 which fits within loops 18 and 18^a.

formed in the upper edges of the plates 15 and 15^a. These plates extend only partially across the cabinet, while the rod 17 extends through the loop 18^a on the plate 15^a and passes over the gap 24, hereinafter described, and enters into the loop 18 a suitable distance, as shown in Figure 10, thus forming a substantial support over which the web of toweling is drawn and against which the 10 towel is pressed by the action of the hinged portion of the forward gripper. This hinged portion comprises a plate 19^a pivoted at a point intermediate to its longitudinal edges on a rod 20 mounted in the side walls of the 15 casing, said hinged portion having an upper edge 21 to bear on the upper portion of the plates 15 and 15^a and clamp the towel thereon, and a flanged lower edge 22 in angular relation to the main body of the plate and 20 with which the towel web contacts for swinging the hinged portion against the towel web and squeezing or clamping it on the surfaces of the plates 15 and 15^a, thereby arresting feed of the towel when an outward horizontal pull is imparted thereto. A 25 limited downward pull is allowed until the hands of the user contact with the shelf 5, when such movement will be arrested and will indicate to the user that a sufficient length of towel has been delivered for wiping purposes. The towel is then drawn out through the opening where it can be conveniently reached and pull in this direction will be limited by the action of the gripper.

30 The plates 15 and 15^a have rearwardly projecting ears 23, preferably integral therewith, and in parallel relation with a space or gap 24 between them near the middle of the cabinet. In these ears and the side 40 walls of the casing rods 25 and 25^a are mounted, forming pivots for rear gripper hinged portions 26 and 26^a of substantially the same form as the corresponding members of the forward gripper and mounted to 45 clamp the web of the other towel against the upper portion of a plate 27 which is vertically arranged in the casing and extends entirely across the same from side to side and is rigidly secured to the side walls of 50 the casing by rivets 16. These gripper members 26 and 26^a have the angle portions 28 which are engaged by the loose webs of the towel for tilting the upper portion of the members against that portion of the web passing over the plate 27 and clamping said portion when an outward horizontal pull is applied to the towel. A direct downward pull is permitted but this in turn will be limited by the shelf 5.

55 A web of towel from the roll 10^a is carried up in the rear of the panel 4 and in front of the guards 12 over the plate 27 and between it and the members 26 and 26^a and allowed to hang in this position until the forward web has been used. When this has

been done, the web 10^a will be visible to the user and he may reach into the casing, draw out a predetermined length, and then pull it forward to the front of the cabinet where it can be conveniently used.

70 When the towel roll 10 has been exhausted, the web 10^a will then be visible and accessible to the user and he may reach through the opening in the front of the cabinet, grasp this web and draw it forward and use 75 it in the same manner as the web of the first roll. When the janitor discovers that one towel roll is exhausted, he may move the roll 10^a into the chamber 9, pass the web of the 80 towel through the gap in the guide 12 as shown in Figure 3 and pass the end of the web over the rod 13, and from thence to the forward gripper where it can be used in the 85 same manner as the first roll. Then when the laundry man brings around a clean supply of toweling, a clean roll may be put in the chamber 9^a and the web carried up along the wall 4 with its loose end supported by the rear gripper ready for use when the forward web is exhausted. Instead of changing the position of the roll 10^a, the janitor 90 may leave it in the chamber 9^a and carry the web up over the rod 13 and from thence to the forward gripper, and when a fresh roll is delivered, the roll 10^a may be moved to the chamber 9 and its web passed out through the gap in the guide. The rolls may 95 be handled either way, the result being the same, and the user always having a supply 100 of clean towel at hand adjacent to the opening in the front of the cabinet.

I prefer to place the roll 10^a in the compartment 9^a for convenience in passing the loose ends to the grippers and avoiding the necessity of crossing one web of the towel 105 with another.

In Figure 9 I have shown in dotted lines how the loose end of the towel is carried forward over the rear grippers to the front one, passing through the narrow gap or opening 24 that is formed between the supports for the rear grippers.

In Figures 4 and 5 I have shown a modified construction which consists in providing a single clean roll compartment 29 in the bottom of the casing and carrying the clean towel therefrom up in the rear of a panel 30 to the rear of the grippers. In the top of the cabinet a chamber 31 is provided for the roll of clean toweling having a wall 32 over which the towel web passes to the forward gripper and from thence the soiled towel drops by gravity into the compartment 33 in the lower portion of the cabinet. A door 34 is provided for access to this compartment. The manner of mounting the towel webs in the grippers is the same as heretofore described, the only difference being that instead of having both rolls in the bottom of the cabinet, as heretofore shown, one 125

roll is in the top and one in the bottom. The opening in the front is substantially the same and the shelf below the opening forming a stop for the hands of the user and a guide for the soiled towel is as shown in the previously described figures.

In Figures 6 and 7 I have shown another construction of cabinet in which the soiled towel chamber 35 occupies the entire lower portion of the casing and chambers 36 and 37 are provided in the upper portion of the cabinet for the clean towel, a wall 38 pivoted at 38¹⁰ separating these chambers one from the other. Removable guide-rods 39 and 40 are provided, over which the web of towel from the upper roll passes to the rear grippers and a wall 32, corresponding to the one shown in Figure 5, is provided for the other towel chamber, over which the web 15 of towel from the lower roll passes to the front gripper. As soon as this lower roll is used and the soiled towel deposited in the bottom of the cabinet, the person standing in front may reach through the opening 20 and grasp the rear web, pulling it down and forward to its wiping position. He can use it in this manner until the janitor or other person fills the cabinet, when the web will be carried forward to the front gripper 25 and the roll moved to the lower compartment a clean roll being placed in the upper chamber and the web dropped down and delivered to the rear grippers, as before. In this way I am able to maintain a continuous supply of clean toweling and at the 30 same time prevent a waste or undue use thereof, and also prevent the necessity of returning a partially unused roll to the laundry or requiring a special trip to fill a cabinet when the laundryman finds the supply is nearly exhausted, and there is not a sufficient amount to last until he makes 35 another trip.

The advantage of the transversely divided gripper will be appreciated when it is understood that the laundryman may find a partially used roll and to shift it from one gripper to the other, if the gripper was not divided, would necessitate withdrawing the soiled end entirely from its gripper and reinserting or threading it through the other gripper. By having the gap between the sections of the gripper, it is only necessary to turn the web of towel edgewise, as indicated in Figure 9, and slip it through the gap between the grippers from the front to the rear of the cabinet. I thus avoid the necessity of pulling the soiled portion of towel back through the gripper to the end of the towel.

I claim as my invention:

1. A towel cabinet comprising a casing having compartments for webs of clean toweling, towel grippers mounted in the upper portion of said casing and said cas-

ing below and in front of said grippers having an opening through which the user may grasp the clean towel, said grippers being arranged one in front of the other and portions of said grippers being divided transversely to allow a towel web to be transferred conveniently from the rear to the forward gripper. 70

2. A towel cabinet comprising a casing having a receptacle for webs of clean toweling and forward and rear towel grippers mounted in the upper portion of said casing, the front of said casing having an opening beneath and near said grippers through which the clean towel web can be conveniently reached, said grippers permitting a direct downward feed of the towels and clamping and preventing such feed when an outward pull is exerted on the towel webs, a portion of the forward gripper extending continuously across said casing and portions of said grippers being formed in sections with a gap between them through which the web of clean towel may be transferred from the rear gripper to the forward one. 75

3. A towel holder having a delivery opening in its upper portion and a soiled towel chamber below said delivery opening, main and reserve towels in said holder, one above said delivery opening, the webs of said main and reserve towels depending in the rear of said opening, said main towel web being in front of said reserve web and normally concealing it until said main web is exhausted, said main and reserve webs having a delivering means adjacent said opening, said main web being stretched to said delivering means and pulled thereover by the user, and said reserve web being stretched to said delivering means when said main web is exhausted. 80

4. A towel cabinet comprising a casing having receptacles for clean toweling and an opening in its front wall through which the user may grasp the webs of toweling, forward and rear grippers mounted in said casing near said opening, portions of said grippers being divided transversely forming a gap therein and a removable rod supporting said divided portions and normally bridging said gap, said gap when said rod is removed permitting the web of towel in the rear gripper to be transferred to the forward gripper, the towel web passing through 100 the gap between the divided portions of the gripper. 105

5. A towel cabinet comprising a casing having a receptacle for a web of clean toweling and an opening in its wall through which access may be had to the towel, a gripper mounted in said casing near said opening and composed of sections supported on the side walls of said casing at their outer ends and having their inner ends 110 115 120 125 130

spaced apart to form a gap between them to allow the insertion of a web of clean towel, and a movable gripper jaw extending across said casing in front of and near said sections for gripping the towel web against said sections, said movable jaw permitting a direct downward pull and checking an outward pull on the towel.

6. A towel cabinet comprising a casing having compartments for clean toweling, 10 towel grippers mounted in said casing for grasping the webs of clean toweling and limiting outward horizontal pull thereon, said grippers being arranged one in advance 15 of the other and comprising normally fixed and movable members, and the movable member of the rear gripper and a stationary member of the forward gripper being divided transversely to allow the transfer of 20 the towel web from the rear to the front gripper.

7. A towel cabinet comprising a casing having compartments in the top and bottom thereof for rolls or bolts of clean toweling, 25 and grippers mounted in said casing intermediate to said compartments for supporting the loose ends of the rolls of toweling one in front of the other in position to be grasped and drawn forward by the user, 30 said grippers being arranged one in front of the other, the rear towel being reached by the user when the towel in the forward gripper has been exhausted.

8. A towel cabinet comprising a casing, 35 compartments for rolls of clean toweling in the top and bottom of said casing, grippers mounted in said casing intermediate to said compartments and adapted to support the loose ends of the towel rolls, one gripper being arranged in advance of the other adjacent an opening in said casing through

which the user may grasp the towel, and one gripper being divided transversely to allow the web of a partially used towel to be shifted through the gap between the gripper 45 sections from one gripper to the other.

9. A towel cabinet comprising a support and webs of clean toweling therein, towel feed regulating devices mounted in said support, one in advance of the other, one regulating device being adapted to allow the passage of the clean towel web transversely therethrough to move it from one regulating device to the other, for the purpose specified. 50

10. A towel cabinet comprising a support, towel grippers mounted therein for regulating the feed of the clean towel, one gripper being arranged in advance of the other and one gripper being adapted for a shifting 60 movement of the towel web transversely thereof when the towel in the other gripper has been used.

11. A towel cabinet comprising a casing having compartments in the top and bottom 65 thereof for webs of clean toweling hanging one in front of the other, and said casing provided with a delivery opening in its upper portion, a towel feed regulating device provided adjacent to said opening, and over 70 which the web of clean towel passes in position to be grasped by the user, and means in the rear of said feed regulating device and adjacent thereto for supporting the loose end of the web of reserve toweling in 75 the rear of the main web, said loose end becoming visible and accessible to the user through said opening when the first towel is exhausted.

In witness whereof, I have hereunto set 80 my hand this 25th day of January, 1922.

FRANK M. STEINER.
